MOTOR AND MOTOR HORN

Application filed April 25, 1925. Serial No. 25,741.

This invention relates to a functionally and structurally improved acoustical warning signal, capable of use in numerous different associations, but primarily intended for employment on vehicles such as automobiles.

It is an object of the invention to provide an apparatus of this character embodying relatively few parts each individually simple and rugged in construction, these parts being largely capable of manufacture by automatic machinery, and moreover capable of assembly by relatively unskilled labor, and when so assembled providing a warning signal operating over long periods of time with freedom from electrical and mechanical difficulties.

A further object of the invention is that of furnishing a signal which will produce a sound of maximum carrying power and pleasing tone and which, moreover, will not alarm pedestrians.

With these and further objects in mind, reference is had to the attached sheets of drawings illustrating one practical embodiment of the invention, and in which:-

Fig. I is a longitudinal section through a motor-horn containing the invention, taken through the sectional-line I—I of Fig. III; Fig. II is a horizontal section of the same motor-horn, taken through the sectional-line II—I of Fig. III, at right-angles to Fig. I;

Fig. III is a transverse section through the same horn;

Fig. IV is a face-view of the diaphragm; and

Fig. V is a detail, showing the rear face of the reciprocating pole-piece and of a flat spring connected to it.

By means of a laterally-extending arm 1 integral with or attached to a stout ring 2, which carries an amplifying-horn 3, the entire structure may be secured at the desired location upon an automobile or other suitable support. The margin of a diaphragm 4 is clamped against the rear face of said ring 2 by the front face of a stout rear clamping-ring 5, which supports the motor-frame and also a shell or rear casing that encloses the tire motor. The opposed faces of said rings

2 and 5 are preferably inclined forwardly, as indicated; and the normally-flat margin of the diaphragm is clamped between these opposed faces, as by bolts, preferably with washers interposed. When said clamping-faces are forwardly inclined, their forward inclination imparts a flexing-stress around the outer portions of the diaphragm, and tends to maintain the central portion of the diaphragm normally flexed forward. Preferably the diaphragm may be provided near its margin with reverse annular grooves 6, which facilitate the vibrating of the diaphragm. Through the center of the diaphragm extends a screw-threaded rod 7 secured thereto in any desired manner and which provides or mounts a reciprocating pole-piece 8 whose solenoid-like movements (as below set forth) coact with the resiliency of the diaphragm to vibrate the latter. The rear face of said pole-piece 8 is cylindrically concave to conform to the pathway of armature-arms (to be described).

Preferably a relatively-stiff spring serves as a positive limit to the rearward movement of said pole-piece. It is here shown as a flat spring 9, transversely disposed behind said ring 5, and anchored thereto at its outer end, while its inner end is connected to the pole-piece. This spring, when present, prevents said reciprocating pole-piece from contacting with the rotary armature; it also controls the pathway of said pole-piece; and it further assists the resilience of the diaphragm in restoring the latter to normal position after each rearward movement towards the motor.

The motor-frame 10 has outwardly-turned feet which are secured to inwardly-projecting portions of the rear ring 5, as by screws or bolts 10' (see Fig. III). This frame 10 is provided with suitable journal-bearings for the ends of a rotary armature-shaft 11, which carries an armature and an adjacent commutator. The armature consists of a hub having one or more, preferably two, symmetrically-arranged pairs of oppositely-disposed arms or spools, each arm terminating in a shoe 12 whose outer face is cylindrically convex to conform to the concave face of said reciprocating pole-piece 8. Each of said spools

is independently wound, with like turns, in circuit with its own commutator-segment, said commutator having one segment for each arm of the armature. A yoke 13, of magnetic material, and preferably of laminated structure, is mounted on the motor-frame to encircle the armature at right-angles to its shaft, the two ends of said yoke terminating in parallel inturned feet 14, separated by an air-gap within which reciprocates said pole-piece 8. Diametrically opposite to said air-gap, said yoke is provided with its one fixed pole-piece 15, whose face is cylindrically concave, like the face of the opposite and complementary pole-piece 8, to conform to the pathway of the armature-shoes 12 as they travel around successively confronting the two complementary pole-pieces. A field-coil 16, suitably supported in a zone parallel to the axis of the armature, operatively encircles the air-gap and the reciprocatory pole-piece therein.

One of the two main circuit-wires leads from any suitable source of current, as the storage-battery of the automobile, to one end of the field-coil wire; and the current passes thence, through the field-coils, to one of the two brushes presented by the motor-frame in operative relation to the commutator. The current passes out from the opposite brush to the other main circuit-wire. The opening and the closing of the circuit through the motor is controlled by any suitable switch, preferably one actuated by a conveniently-located push-button (not shown).

When the motor is energized by the admission of current, its armature rotates; and as each one of its (four) shoes 12 comes within the magnetic field of said fixed pole-piece 15, its opposite or complementary shoe simultaneously comes within the magnetic field of the aforesaid air-gap, and a solenoid-like effect is exerted upon the reciprocatory pole-piece 8, drawing the latter and the center of the diaphragm rearwardly against the increasing tension of the diaphragm itself (and against the increasing tension of said limiting-spring 9); and as the opposite shoes of each pair of arms pass out of said magnetic fields, the stored tension of the diaphragm (and of spring 9) overcomes the solenoid-like effect and restores the reciprocatory pole-piece and the center of the diaphragm to (and possibly beyond) normal position. Consequently the revolutions of the armature are attended by a regularly-recurrent to-and-fro vibration of the diaphragm, which sets up sound-waves corresponding approximately to a sinusoidal curve. That is, the new motor-horn emits a practically-pure musical note of great volume, which may be amplified by providing a trumpet of the proper dimensions corresponding to the frequency of the vibrations.

The annular reverse grooves 6 might be dis-

pensed with; but they are preferably utilized because, when present, less power is required for vibrating the diaphragm, or the same power produces sound-waves of greater amplitude. The angle of inclination of the opposed faces, between which the diaphragm is clamped, might be varied considerably, and indeed the diaphragm might be so clamped as to lie normally in a flat plane, its resiliency serving, on reaction, to complete the full vibration; but some appreciable forward inclination of said faces, and the resultant normal maintenance of the forward bulge of the diaphragm, are preferred as affording a more positive return-action of the diaphragm.

The motor has a plurality of oppositely-disposed arms with shoes, here disclosed as four in number, constituting two pairs. It is preferable to have at least two pairs, or four arms; because this ensures a more steady and dependable rotation of the motor. And, for vibrating the diaphragm of a motor-horn, it is preferable to have not more than four arms, lest the frequency of the resultant vibrations be too high, and the resultant signal be too high-pitched or shrill.

It is obvious that the novel diaphragm, constructed and mounted as herein disclosed, might be vibrated by other actuating-means than as herein set forth; but it is especially designed to be vibrated by a rotary electric motor, and particularly by one actuating a reciprocatory pole-piece. It is also obvious that the novel motor might be employed in any service where a reciprocatory motion is to be produced; but it is especially designed for vibrating an acoustic diaphragm, inasmuch as the latter has a natural frequency of its own, and therefore reacts on the motor as an escapement or regulator. A motor-horn combining the novel diaphragm and the novel motor, both as herein disclosed, when energized by a 6-ampere current, emits a beautiful and smooth signal that can be recognized approximately two miles away; yet, to persons near by, the signal is neither harsh, shrill nor over-startling.

The invention has now been described in full detail; and it is to be understood that the following claim is intended to cover all of the generic and specific features of the invention herein described, and all statements of the scope of the invention which as a matter of language might be said to fall therebetween.

Having thus described my invention, I claim and desire to secure by Letters-Patent the following:

A warning signal including, in combination, a vibratory diaphragm, a pole piece extending rearwardly thereof and secured thereto, a yoke including spaced arms between which said pole piece is disposed, a rotary armature extending within said yoke and having its arms moving in a path adjacent said pole piece, a commutator forming a part

of said armature, brushes coacting with the segments of said commutator, windings associated with the arms of said armature and connected to said commutator, a field coil associated with said yoke and in line with said pole piece, and inturned foot portions forming a part of said yoke arms and extending adjacent said pole piece and said coil.

In testimony whereof I affix my signature.
